Primary Examiner — Derrick E Holland*Assistant Examiner* — Janice Julia Patyk(74) *Attorney, Agent, or Firm* — Kathleen Y. Carter; Betty Joanne Zea(57) **CLAIM**

The ornamental design for an applicator dome, as shown and described.

DESCRIPTION

FIG. 1 is a perspective view of an applicator dome, showing our new design;

FIG. 2 is a top plan view thereof;

FIG. 3 is a bottom plan view thereof;

FIG. 4 is a front view thereof;

FIG. 5 is a first side view thereof;

FIG. 6 is a back view thereof; and,

FIG. 7 is a second side view thereof.

The broken line portions of FIGS. 1-7 show unclaimed subject matter only and form no part of the claimed design.
